[57] CLAIM

The ornamental design for a hose clamp, substantially as
shown and described.

DESCRIPTION

FIG. 1 is a front elevational view of a hose clamp showing
my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a perspective view thereof, showing the clamp
in a closed position.
